W. G. Townsend,
Atty.

UNITED STATES PATENT OFFICE.

JOSEPH OLMSTED, OF NEW YORK, N. Y.

TELEPHONE-TRANSMITTER.

SPECIFICATION forming part of Letters Patent No. 252,132, dated January 10, 1882.

Application filed October 14, 1881. (No model.)

To all whom it may concern:

Be it known that I, JOSEPH OLMSTED, a citizen of the United States, residing in New York, county of New York, and State of New York, have invented a new and useful Telephone-Transmitter, of which the following is a specification.

My invention consists in a novel construction of the electrodes or circuit-controlling portion of the instrument, whereby the operation of the instrument in transmitting sounds is greatly improved and the constancy of the adjustment increased, and whereby, also, the occurrence of the hissing, sputtering, and other foreign sounds in the receiver, caused by abnormal action of the transmitter, are largely avoided.

My invention also consists in other novel features of construction, relating more particularly to the adjusting devices, and the means employed for holding the electrodes in position, the nature of which will appear from the following description and the accompanying drawings, in which—

Figure 1 is a top or plan view of the instrument, showing the front of the transmitter-casing, the diaphragm, and the mouth-piece in horizontal section. Fig. 2 is a side view, showing the supporting rod for the pivoted electrodes in section. Fig. 3 shows a modified construction of the contacts or electrodes.

In telephone-transmitters as heretofore usually constructed but one electrode has been employed for making contact with the electrode or contact which is attached to or connected with the diaphragm so as to be put in motion thereby, and in those instances where two electrodes have been used resting upon the diaphragm springs have been employed for compelling contact, and independent adjusting devices have been used for the two electrodes.

My improved transmitter differs from prior instruments of its class in that a multiplicity of electrodes is employed resting against the electrode connected with the diaphragm, each electrode being freely pivoted so as to rest by its own weight upon the diaphragm-electrode, while, further, said electrodes have a common support adjustable by suitable devices, so that they are adjusted together. The electrodes

being symmetrically arranged, and each resting by its own weight upon the common electrode carried by the diaphragm, the natural and normal contact is the same for all, whereas in the case of spring-supported electrodes there are no means of determining the force which tends to hold the electrodes in contact with the diaphragm, and it is hence impossible to have the same initial or normal contact for all. Moreover, as there is a multiplicity of electrodes a defect in one will not seriously affect the operation of the instrument, and as the electrodes are hung upon a common adjustable support the initial force tending to hold them in contact can be readily adjusted for all by one and the same adjustment. The form of the pivoted or swinging electrode employed is also peculiar, and is such that an adjustment to increase the initial force tending to hold it in contact with the diaphragm-electrode will also vary the angle of impingement of the electrode carried by the diaphragm with the pivoted electrodes and decrease the tendency of the latter to yield or move under the action of the diaphragm-electrode.

In the accompanying drawings, A represents the front of the transmitter-casing, and B the mouth-piece.

D represents the diaphragm clamped against a plate, C, of insulating material, by a screw or bolt or other suitable means.

E is a metal ring or washer bearing against the diaphragm. The plate, diaphragm, and washer are clamped against the inside face of the front plate.

F represents a metal rod projecting at right angles from the diaphragm, and carrying at its end a cross-arm, G, of any suitable material, which constitutes the electrode or contact attached to or connected with the diaphragm so as to be put in motion thereby.

At H is represented a series of pivoted plates, preferably of carbonized paper or cardboard, and strung upon a metal rod, I, which is fixed in knobs K, of hard rubber or other insulating material, screwed upon the ends of bolts L. The latter pass through the diaphragm and the front of the casing, as shown, and are provided with nuts M, whereby they may be adjusted longitudinally backward and forward, carrying with them the freely-pivoted

electrodes H. The under edge of the electrodes H, or the portion resting upon the rod G, is inclined, as shown, so that the latter impinges against the edges of electrodes H at an angle. As will be seen, any movement of the rod G forward will tend to raise the ends of the plates or electrode H. As shown in the drawings, the rod I and the cross-arm G are in the same horizontal plane, so that the movement imparted to the plates by the movement of the cross bar G is due only to the sliding movement of the rod G against the inclined edge. It is obvious that the readiness with which the plates will move depends upon the angle of impingement of rod G, and that if the rods G and I be brought nearer together the angle of incidence or impingement will be increased and the plates will yield less readily. This adjustment is accomplished by means of the rods L and bolts M. The same adjustment serves also to vary the initial or normal force tending to bring the electrodes H into contact with the rod G, since the nearer the supports G and I are brought together the greater will be the portion of the weight of the plates H resting upon the rod G. It is obvious that the latter adjustment for degree of force with which contact is made may be still accomplished, although the rods G and I are not in the same horizontal plane, and that the adjustment for angle of incidence or directness of contact, and readiness with which the plates will yield to movement of G, may also be made under such conditions.

The plates H, as I have before remarked, are preferably of carbon formed by carbonizing card-board or other analogous material, after the manner employed in making carbon strips from paper or card-board for the incandescent portion of electric lamps. They may, however, be formed in other ways; but I prefer to make them in the manner specified, since it is simple, and the plates, being light, give a delicate and sensitive contact. I do not, however, limit myself to carbon as the material for the plates, since they may, if desired, be made of thin plates of any desired metal—as, for instance, platinum—the electrode G being in this case preferably formed with its contact-surface of carbon, although I do not limit myself in the latter particular, nor do I desire to limit myself, so far as the multiple-pivoted electrodes are concerned, to the particular form shown, it being feasible to use other constructions, since this portion of my invention consists in freely pivoting or supporting a number of independent electrodes so that they will rest by gravity against a common electrode carried by the diaphragm, and also in pivoting or supporting a number of electrodes upon the same adjustable piece.

The form of the electrode G, and the manner of attaching the same to the diaphragm, or supporting it so that it may be put in motion by the latter, may also be varied in many ways. I also wish it to be understood that the devices for adjusting the part upon which the

multiple electrodes are supported may be varied without departing from the spirit of the invention.

The electrical connections for the instrument are made at the points P and N, the latter being a binding-post upon the end of the metal rod I. The circuit is from N through I, electrodes H, electrode G, diaphragm D, and out at P.

In Fig. 3 is shown a modified construction of the electrodes. In this case the electrode S, attached to the diaphragm, has an inclined face, the pivoted gravity-electrode R resting upon the same at one corner. In this case the necessary adjustment would be made by moving the support for R in a vertical plane, although other methods of adjustment may be employed.

What I claim as my invention is—

1. The combination, in a telephone-transmitter, of a contact electrode carried by the diaphragm, and a series of independently-pivoted simple electrodes resting independently and by their own weight against the electrode carried by the diaphragm.

2. A compound electrode for a telephone-transmitter, consisting of a series of independently-yielding variable contact-electrodes, in combination with a common adjustable support for said electrodes.

3. A compound electrode for a telephone-transmitter, consisting of a number of simple freely-pivoted electrodes resting by the action of gravity upon the opposite electrode, in combination with a common adjustable support upon which said electrodes are pivoted.

4. A compound electrode for a telephone-transmitter, consisting of a series of parallel independently-pivoted carbon plates fixed upon a common support.

5. The combination of a series of parallel independently-pivoted carbon plates and an adjustable common support upon which said plates are pivoted.

6. A compound electrode for telephones, consisting of a number of parallel plates independently pivoted and resting with their edges upon the opposite electrode.

7. A compound electrode for a telephone-transmitter, consisting of a number of parallel pivoted plates formed of carbonized card-board, paper, or equivalent material.

8. An electrode for a telephone-transmitter, consisting of parallel plates strung upon a conducting-rod.

9. The combination, with an electrode connected with the diaphragm of a transmitter, and having a curved contact-surface, of an electrode consisting of a thin sheet of conducting material resting with its edge against the diaphragm-electrode.

10. A contact-electrode for a telephone-transmitter, consisting of a thin sheet of carbonized paper or thin card-board, said electrode being mounted so as to rest with its edge against the electrode with which it makes contact.

11. A contact-electrode for a telephone-trans-

mitter, consisting of a carbonized plate of paper or card-board, in combination with a supporting-rod of metal passing through said plate.

12. The combination, substantially as described, of a pivoted-plate electrode resting with its inclined edge against its opposite electrode, and an adjustable support for the first electrode, all combined as described, so that by adjusting the support of the pivoted electrode 10 the angle of impingement of the second electrode may be varied.

13. The combination of a compound electrode consisting of a series of pivoted parallel plates, an electrode connected to a diaphragm, against 15 which electrode the parallel plates bear with inclined edges, and an adjustable support for said pivoted electrodes, adjustable to and from the electrode connected with the diaphragm.

14. The combination of a series of parallel 20 pivoted plates, a cross-bar connected to a diaphragm, against which bar the edges of the piv-

oted plates rest, a conducting-bar upon which the pivoted plates are strung, and supporting-rod for said conducting-bar, connected at right angles thereto, and adjustable longitudinally. 25

15. The combination of rod E, attached to the diaphragm cross-bar G, pivoted plates H, resting upon the bar, with their lower edge inclined thereto, rod I, and adjustable rods L, substantially as described. 30

16. The combination of a pivoted electrode, and an adjustable support for the same, adapted to be moved to and from the electrode against which said pivoted electrode bears, so as to vary the initial pressure in the manner described by shifting the point upon the pivoted electrode at which it makes contact and is partially supported. 35
